CLAIM

The ornamental design for an air conditioner as shown and described.

DESCRIPTION

FIG. 1 is a first perspective view of an air conditioner showing our new design;

FIG. 2 is a second perspective view thereof;

FIG. 3 is a third perspective view thereof;

FIG. 4 is a left-side view thereof;

FIG. 5 is a right-side view thereof;

FIG. 6 is a front view thereof;

FIG. 7 is a back view thereof;

FIG. 8 is a top view thereof; and,

FIG. 9 is a bottom view thereof.

(Continued)

The broken lines shown in the figures are for the purpose of illustrating portions of the air conditioner and form no part of the claimed design.
